UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

WEB-RENEWING DEVICE.

1,402,989.

Specification of Letters Patent. Patented Jan. 10, 1922.

Application filed May 31, 1918, Serial No. 237,448. Renewed June 13, 1921. Serial No. 477,346.

To all whom it may concern:

Be it known that I, HENRY A. WISE Wood, a citizen of the United States, residing at New York, in the county of New York and State of New York, have invented a new and useful Web-Renewing Device, of which the following is a specification.

This invention relates to mechanism for providing a continuous supply of web for printing presses and other machines by connecting a fresh web to the end of an expiring web.

The principal objects thereof are to provide an improved device for this purpose which will operate effectively without stopping the press or slackening the speed, and at the same time to obviate the necessity of moving the fresh web roll bodily after it is put in position on the press and the necessity for threading the fresh web into place by hand; to provide means whereby a direct action between the expiring and fresh rolls is secured for pressing one against the other so as to unite the two webs under some degree of pressure; and to avoid complicated and troublesome constructions for the purpose of making the new web adhere to the old one.

The webs are united, according to the present invention, by placing paste on the end of the new web, revolving the new web roll at surface speed, and moving the expiring web and preferably its roll bodily into contact with it. A perfect splice is made between them and by throwing a knife against the exhausted stub the expired web is severed and the stub stopped. It can then be taken out, its bearings moved back, and a new web roll shaft set into them before the other web is exhausted, and then the operation can be repeated or, more properly speaking, reversed.

The invention also involves improvements in details of construction and combinations of parts as will appear.

Reference is to be had to the accompanying drawings, in which—

Fig. 1 is an end elevation of the paper roll end of a web press showing a preferred embodiment of this invention;

Fig. 2 is a horizontal sectional view on the line 2—2 in Fig. 1;

Fig. 3 is a diagrammatic view showing the position of the parts as the free end of

a new lower roll is spliced to the upper running web from a nearly exhausted stub, and

Fig. 4 is a similar view showing the opposite site operation, that is, the splicing of a new upper roll to the lower exhausted web.

Several web-renewing devices have been invented for the general purpose of uniting the new web to the old one without stopping the press or slackening its speed. Some of them involve manipulation of the new web roll, which is of great weight, and others the diversion of the running web out of its path so as to paste it to the new roll by pressing a roller against it at a point between the old stub and the first guide roller. The latter arrangement involves some difficulties because the roll which is pressed against the web has to be started into operation by contact with the web running at full speed and by its motion against the web it has to lengthen the course of the web.

This invention, as has been stated, does not involve either of the motions just above mentioned, but in their place the old web roll stub itself is moved, thus not making any new angle in the running course of the web or increasing in any way the difficulty of its operation.

Referring particularly to Figs. 1 and 2, it will be seen that I have illustrated the end of the frame 10 of a web press, the two side frames constituting the support for the whole mechanism shown. On these frames are mounted bearing brackets 11, one pair for each web roll A or B. Each of these brackets 11 slides up and down on vertical guides 21 on the edges of said frames, and is provided with a bearing for one end of a paper roll spindle 12. These are shown as having covers or caps and are of a well-known type. The usual brakes 13 are provided for the paper roll spindles which have brake pulleys 14. The brakes are supported on studs 15 mounted on stationary projections from the side frames 10. These brakes can be released entirely as the paper rolls become nearly exhausted so as not to interfere with the movements of the paper roll stub up and down the frame. Details of the brake mechanism are not described herein as they do not constitute a part of this invention, and any desired type can be employed.

The brackets 11 are mounted to slide up

and down on the vertical edges of the side frames 10, and they are provided with threaded projections 16 for receiving screws 17 and 18 arranged in pairs on each side of the press, one for each of the brackets. The screws 17 and 18 on the same side are arranged in alignment and two of them are journaled in a stationary bracket 19. They are rotatable independently of each other. The opposite end of each one of these screws is journalled in a bracket 20.

Worm wheels 23 are mounted on brackets 24 fixed on the side frame. The worm wheels 23 are designed to be operated by worms 25 on transverse shafts 26 carried in bearings on the side frames. Each of these shafts is provided with a hand wheel 27 by which it is designed to be operated. The worm wheels 23 are provided with clutch ends 29 on opposite sides which are adapted to be engaged by clutch collars 30 on the adjacent ends of the screws 17 or 18 so as to permit transmission of rotation from the hand wheel to a shaft above it or below it, as may be desired, these clutch collars 30 of course being movable the distance required for this operation. By rotating the hand wheel the two shafts 17 or 18, as the case may be, on the two sides of the press are turned and the brackets 11 carried thereby can be raised or lowered.

Mounted between the two shafts 17 and 18, and preferably extending from the bracket 19 which supports their adjacent ends, is an arm 31 on each side. These carry a transverse shaft 32 at their end which is provided with a saw-toothed knife 33. On the operating end of this shaft 32 is an arm 34 secured to it and adapted to be held normally in a horizontal position by a spring pin handle 35. A slight outward pull on this handle releases it and allows the operator to swing the arm 34 so as to oscillate the knife blade 33 either up or down, as for example into either one of the positions indicated in Figs. 3 and 4. This cuts off the expiring web and stops its stub from revolving.

As has been the case in some of my devices heretofore designed for this general purpose, the press mechanism is designed to operate a vertical shaft 41 on one of the side frames, brackets 42 being provided for supporting it and furnishing its bearings. This supplies power through bevel gears 43 and friction wheels 44 and 45 to operate a shaft 46 having a friction bearing 47 designed to be controlled by a handle 48 fixed to the shaft. This handle is normally held by a catch 49 engaging a pin 50 and mounted on the side frame. When this catch is released the handle is swung over by a spring 51 which turns the shaft on its own center. Fixed on this shaft also is a frame comprising two arms 52 supporting a shaft 53 extending across the machine which carries friction

rolls 54 for rotating the fresh web roll as is well understood in this art. The shaft 46 is connected with the shaft 53 by two gears 55, in the case shown above the driven gears 43, and by three gears in the case shown below, so as to transmit the rotation to the web roll in the right direction.

The operation of the device will be clearer from an inspection of Fig. 3. As is usual, the idle reserve roll 13 has been pasted at its end. As the upper web roll A was about to become exhausted the next to the lowest handle 48, shown in Fig. 1, was released and brought up so as to bring the roll B up to web speed. Then the brake operating on the spindle of roll A was released manually and the clutch sections connecting the worm wheel 23, shown at the top of Fig. 1, with the screw 18 below it were brought together. Now the operator, leaving things in that condition, turns the hand wheel 27, at the top of Fig. 1, and brings down the web roll A from the dotted line preferably all the way to the full line position in Fig. 3, in which it contacts with the new web roll B. If it is not moved into contact bodily the two webs will have to be brought together, and I prefer to press them together between their respective rolls. It will be seen that this operation does not bring any additional angle into the line of motion of the web, and thus introduces no complications. It simply swings this part of the web as a whole about the guide roll 60 to which it passes, leaving the course of the web straight between the web roll A and this guide roll.

Now the spring pin handle 35 is drawn out and the arm 34 turned so as to bring the blade 33 up around to the right into the position shown in Fig. 3 against the remote side of the expiring stub, thus severing the exhausted web from its spindle, and that spindle can be raised again by operating the same hand wheel 27. Its rotation stops of course.

When the roll B is about to become exhausted a new web roll A is put into the upper bearings, as indicated in Fig. 4, and then by manipulations similar to those above described the exhausted stub B is brought up into the full line position in that figure, and the webs secured together as above described. Then the arm 34 is brought around in the opposite direction so as to sever the old web, as indicated in Fig. 4.

This is a simplification in several respects and an improvement over the prior devices which I have designed for this general purpose.

Although I have illustrated and described only a single embodiment of the invention, I am aware of the fact that modifications can be made therein by any person skilled in the art without departing from the scope

of the invention as expressed in the claims. Therefore I do not wish to be limited to all the details of construction herein shown and described, but what I do claim is—

- 5 1. A web renewing device comprising two sets of web roll holding devices, one set being movable toward the other far enough to bring the web roll held thereby into contact with the other web roll.
- 10 2. A web renewing device comprising means for moving a nearly exhausted web roll directly toward a new web roll so that the expiring web can be brought into contact with the surface thereof.
- 15 3. In a web renewing device, the combination with holding devices for two sources of web supply, means for guiding both webs from points between them along substantially a single path between them, and means 20 for moving one set of holding devices to move its source of web supply directly toward the other one.
- 25 4. In a web renewing device, the combination with a holding device for a new web roll, and a movable holding device for the expiring web roll, of means for moving the latter holding device radially toward the new web roll so that the expiring web can engage the surface of the new web roll.
- 30 5. In a web renewing device, the combination with means for holding an expiring and a new web roll in position to deliver their webs to a press, of means for rotating the new roll to bring its surface up to the speed 35 of the expiring web, and means for moving one of said rolls to bring its delivery side substantially into contact with the other.
6. In a web renewing device, the combination with holding devices for two web rolls, 40 of means for moving one of said web rolls toward the other until it contacts with the surface thereof, and means for rotating the new web roll at web speed in the same direction at their point of contact.
- 45 7. In a web renewing device, the combination with holding devices for two web rolls, of means for moving a nearly exhausted one of said web rolls toward the other until it contacts with the surface thereof, and means 50 for severing the exhausted web from its stub.
8. In a web renewing device, the combination with holding devices for two sources of web supply, means for guiding both webs from points between them along substantially a single path, means for moving one set of holding devices to bring its source of web supply into direct contact with the other one, and a knife between the two holding devices movable toward either of them 60 for severing either web.
9. In a web renewing device, the combination with holding devices for two web rolls, of means for moving one of said web rolls toward the other until it contacts with the

surface thereof, and means oscillatable between the two rolls for severing the exhausted web from either stub.

10. In a web renewing device, the combination with holding devices for two web rolls, of means for moving one of said web rolls toward the other until it contacts with the surface thereof, and means movable against the remote side of the exhausted stub when in contact with the other web for severing its web.

11. In a web renewing device, the combination with a pair of printing press side frames, of screws arranged along said side frames, clutch sections at the end of said screws, means between two adjacent screws adapted to be connected with either of them, a shaft having means thereon for operating said connecting means, means for rotating said shaft, and brackets having bearings for web roll spindles connected with said screws to be moved thereby.

12. In a web renewing device, the combination with a pair of printing press side frames, of a series of screws arranged along each of said side frames in alignment, fixed bearings on said side frames for said screws, clutch sections at the ends of said screws, a wheel between two adjacent screws having clutch sections adapted to be connected with either of them, a transverse shaft having means thereon for operating said wheel, means for rotating said transverse shaft, and brackets having bearings for web roll spindles connected with said screws on both sides of the machine to be moved thereby.

13. In a web renewing device, the combination with the frame of a printing press, said frame having vertical guides along the edges thereof, of a series of independently rotatable screws arranged in alignment on the frame, rotating means mounted on said frame at the ends of each adjacent pair of screws, manually operated means for operating said rotating means, means for detachably connecting each screw with its adjacent rotating means, and pairs of brackets arranged opposite each other on said frame having bearings for supporting web roll spindles and adapted to move along said guides, each bracket being in screw-threaded engagement with one of said screws, whereby the operation of said rotating means will move the brackets along their guides.

14. In a web renewing device, the combination with the frame of a printing press, said frame having vertical guides along the edges thereof, of independently rotatable screws on the frame, rotating means mounted on said frame at the ends of each adjacent pair of screws, manually operated means for operating said rotating means, means for detachably connecting each screw with its adjacent rotating means, means on said frame having bearings for supporting

web roll spindles and adapted to move along said guides, and means whereby the operation of said rotating means will move the supporting means along their guides.

5 15. In a web renewing device, the combination with two web rolls one of which is movable into surface contact with the other, of means oscillatable between the two rolls for severing the web from either stub after 10 the rolls have contacted.

16. In a web renewing device, the combination of the side frames of a printing press with pairs of brackets supported by said frames on opposite sides of the press having 15 bearings for supporting pairs of spindles of web rolls, brakes for each spindle arranged

in position to operate on the same when the spindle is in normal position, said brakes being adapted to be released from their respective spindles, means for moving said spindles bodily away from the brakes, means for guiding a web from a point between two adjacent web rolls supported by a pair of said spindles, and means located in position substantially half-way between the normal 20 position of two spindles for severing the web from the expired web roll when brought into contact with the new web roll.

25 In testimony whereof I have hereunto affixed my signature.

HENRY A. WISE WOOD.
